UNITED STATES PATENT OFFICE.

MAGNUS SWENSON, OF CHICAGO, ILLINOIS, ASSIGNOR TO THE AMERICAN COTTON COMPANY, OF NEW YORK, N. Y.

COTTON-PRESS.

SPECIFICATION forming part of Letters Patent No. 591,304, dated October 5, 1897.

Application filed October 16, 1896. Serial No. 609,148. (No model.)

To all whom it may concern:

Be it known that I, MAGNUS SWENSON, a citizen of the United States, and a resident of Chicago, in the county of Cook and State 5 of Illinois, have invented certain new and useful Improvements in Cotton-Presses, of which the following is a specification.

This invention relates to improvements in cotton-presses, and relates particularly to 10 improvements in cotton-presses of the type adapted to wind a bat of cotton under pressure into a cylindrical bale, and comprising relatively movable compression-rolls and a core-roll movably supported between them.

Primary objects of the invention are to provide means to guide the bat of cotton around the core-roll or around the bale in process of formation and to prevent sagging and breaking of the bat at the under side of the bale.

To this end my invention consists in the use, in combination with the compression-rolls and the core-roll of a cotton-press of this type, of a belt or endless apron, which passes over both of said compression-rolls and beneath the core-roll or the bale while in process of formation.

The invention also consists of the various other features, combinations of features, and details of construction hereinafter described, 30 and then pointed out in the claims.

In the accompanying drawings a cotton-press embodying my invention is fully illustrated.

Figure 1 is a top plan view of a rotary cotton-press embodying my invention; and Fig. 35 2 is a side view thereof.

Referring now to the drawings, A is the frame of the press; A', the stationary compression-roll; A², the movable compression-roll, which is mounted in sliding bearing-blocks a, fitted to and longitudinally movable in guides or ways a', formed in the press-frame A; A³, the core-roll, supported between the compression-rolls A' A² in sliding bearing-blocks a², fitted to and longitudinally movable in the guides or ways a' in the same manner as the blocks a of the movable compression-roll A², and A⁴ the pressure-cylinder whereby the bale in process of formation 45 is subjected to the desired pressure through the medium of rigid connection between a piston fitted thereto and the bearing-blocks a

of the movable compression-roll. All of the foregoing parts are old and well known in the art and may be of any desired or approved 55 construction and need not be described in detail.

The means for rotating the compression-rolls A' A² are also old, comprising a counter-shaft b, mounted in the press-frame A, 60 adjacent to the compression-roll A'; a second counter-shaft b', mounted in the bearing-blocks a, adjacent to the compression-roll A²; pinions B B', secured to which respectively engage gears B² B³, secured to the shafts of 65 the compression-rolls A' A², said counter-shafts b b' being driven in the usual manner, the shaft b from any suitable source of power and the shaft b' from the shaft b by a chain belt B⁴, adjusted to sprocket-wheels B⁵ B⁶, 70 secured to the said shafts b b', respectively. The driving mechanism shown, however, differs from that heretofore used in the respect that both compression-rolls A' A² are driven through the medium of clutches, thus making provision for disengaging both rolls, so that said rolls may be driven and stopped independently of each other. Any approved 75 form of clutch may be used, as shown. B⁷ B⁸ represent said clutches, one applied to each 80 of the pinions B B'. Said clutches are operated by means of levers b³ b⁴, respectively.

The essential feature of the present invention is a belt or endless apron C, which when in position to effect the objects of the invention passes over both of the compression-rolls A' A² and beneath the core-roll A³ or a bale in process of formation thereon, said belt or apron being long enough to permit necessary travel of the movable compression-roll in the 90 formation of a bale.

As the size of a bale in process of formation increases and the movable compression-roll A² recedes from the stationary compression-roll A' it is obvious that the belt or 95 apron C will be retarded relatively to the surface of said movable compression-roll, thus producing a slight slipping of said belt upon said roll, which will produce a strong frictional engagement between said belt and the movable compression-roll. In practice, however, I prefer to increase the frictional engagement between said belt and the compression-rolls. Any suitable means may be em- 100

ployed for this purpose. As shown, they are as follows: Supported above the stationary compression-roll A', in suitable brackets c, secured to the press-frame A, is a roll C', which bears upon said belt with a light pressure and holds said belt in contact with said stationary roll A' with corresponding force. The roll C' is preferably supported in such manner as to be adjustable toward and from the stationary compression-roll A'. As shown, said roll is supported in bearing-blocks c', fitted to and movable in guides or ways c², formed in said brackets c. Threaded into the brackets at the bottoms of the slots c² are screws c³, upon the heads of which the bearing-blocks c' rest. The roll C' is supported against movement away from the compression-roll A' by means of screws c⁴, which bear upon caps c⁵, between which and the bearing-blocks c' are inserted rubber cushions c⁶, which permit said roll C' to yield slightly away from said compression-roll A'. Obviously when a bat of cotton is passing beneath the roll C' the belt C will be held against the compression-roll A' with great force, which will effectually prevent slipping of said belt upon said roll.

Supported in the bight of the belt C beneath the press is a heavy roll C², the weight of which creates a strong frictional engagement between the belt C and the compression-rolls A' A² independent of other agencies. As shown, axial lugs or projections c⁷ on said roll C² engage guides or ways formed in suitable brackets or standards c⁸. This construction operates to maintain said roll in proper position and also permits desired movement thereof.

In addition to the foregoing instrumentalities I also prefer to use what may be termed a "tension-roll" C³, applied to the movable compression-roll A². As shown, said roll C³ is supported in brackets c⁹, secured to or formed integral with the bearing-blocks a of said movable roll in such position that it will be below the top of the compression-roll A², so that it will not interfere with discharging the bale from the press. The roll C³ is preferably covered with a layer of soft cloth, so that its tendency to cut the belt will be reduced to a minimum.

The operation of my improved press is apparent without a detailed description.

I will now describe the method of discharging a bale from my improved press. The bale having attained desired size and having, preferably, been covered, the clutch B⁷, through which the compression-roll A' is driven, is disengaged. Under these conditions operation of the press by rotating the movable roll A² will force the bale upward from between said compression-rolls, and the belt C, being supported against movement relatively to said compression-rolls, will straighten said belt between the tops of said compression-rolls, thus raising the bale into a position from which it may quickly and con-

veniently be removed, as clearly shown in diagram Fig. 2 of the drawings. The bale having been discharged the belt or apron C 70 may conveniently be depressed between the compression-rolls, so that a core-roll may be placed in the press above the same preparatory to beginning the formation of another bale, in the following manner: The clutch B⁷, 75 which drives the compression-roll A', is engaged, and the clutch B⁸, which drives the movable compression-roll A², is disengaged. The belt C, being held from slipping on the disengaged roll A², operation of the press will 80 form a fold in said belt between the compression-rolls, so that a core-roll may be placed in position in the press above the same in the manner desired. The tension-roll C³ will operate to prevent slipping of the belt C 85 upon the surface of the compression-roll A². In case the tension-roll C³ is not used slipping of the belt upon the compression-roll A² may be prevented by imposing a weight upon said belt where it passes over said compression-roll.

Having replaced the core-roll in the press the movable roll A² is returned to its initial position in the baling operation and the belt drawn taut beneath the core-roll. To effect 95 the tightening of the belt beneath the core-roll, the clutch B⁷ is disengaged, the clutch B⁸ engaged, and the press operated, which will rotate the compression-roll A² and will take up any slack in said belt. The press is then in readiness to begin the formation of a new bale. Preferably, also, stops are provided to limit the approach of the movable compression-roll A² to the stationary compression-roll A'. As shown, lugs d are formed, 105 one on each bearing-block a, which strike lugs d' on the press-frame when the compression-roll A² has attained desired proximity to the stationary roll A'. This construction will prevent cutting or other injury to the belt, 110 which might result if said belt were subjected to a strong pressure between the unyielding compression-rolls and the small unyielding core-roll.

The belt or apron C may be made of any 115 suitable material, as strong canvas, leather, rubber, or the like.

I claim—

1. In a cotton-press, the combination of 120 relatively separable compression-rolls, a core-roll supported between said compression-rolls, a belt or endless apron which passes in contact with and over said compression-rolls and beneath the core-roll, means for simultaneously rotating the compression-rolls so 125 as to thereby drive the belt, and means for allowing the belt to be looped down between said compression-rolls to accommodate the enlarging bale and to apply pressure to the bale, substantially as described.

2. In a cotton-press, the combination of 130 relatively separable compression-rolls, a core-roll supported between said compression-rolls, a belt or endless apron which passes in

- contact with and over said compression-rolls and beneath the core-roll, and means for positively rotating the compression-rolls at the same surface speed, the belt being thereby driven by friction from said compression-rolls, whereby the enlarging bale will loop the belt or apron downward and move said belt against the friction imposed thereon, substantially as described.
10. 3. In a cotton-press, the combination of a compression-roll mounted in stationary bearings, a compression-roll mounted in sliding bearing-blocks, a core-roll mounted in sliding bearing-blocks between said compression-rolls, a belt or endless apron which passes in contact with and over said compression-rolls and beneath the core-roll, means for simultaneously rotating the compression-rolls so as to thereby drive the belt, and means for allowing the belt to be looped down between said compression-rolls to accommodate the enlarging bale and to apply pressure to the bale, substantially as described.
4. In a cotton-press, the combination of two relatively movable compression-rolls, a core-roll supported between said compression-rolls, a belt or endless apron which passes in contact with and over said compression-rolls and beneath the core-roll, means for simultaneously rotating both compression-rolls so as to thereby drive the belt, and means for elevating the looped portion of the belt to eject the finished bale, substantially as described.
35. 5. In a cotton-press, the combination of two relatively movable compression-rolls, a core-roll supported between said compression-rolls, a belt or endless apron which passes in contact with and over said compression-rolls and beneath the core-roll, means for simultaneously rotating both compression-rolls so as to thereby drive the belt, and means for driving only one of said rolls so as to elevate the looped portion of the belt to eject the finished bale, substantially as described.
6. In a cotton-press, the combination of two, relatively movable compression-rolls, a core-roll supported between said compression-rolls, a belt or endless apron which passes in contact with and over said compression-rolls and beneath the core-roll, and means for both simultaneously and independently rotating said compression-rolls, substantially as described.
55. 7. In a cotton-press, the combination of a stationary compression-roll, a movable compression-roll, a core-roll movably supported between said compression-rolls, a belt which passes over said compression-rolls and beneath said core-roll, means to create a strong frictional engagement between said belt and compression-rolls, and means for driving said compression-rolls either simultaneously or independently, substantially as described.
65. 8. In a cotton-press, the combination of a stationary compression-roll, a movable compression-roll, a core-roll movably supported

between said compression-rolls, a belt which passes over said compression-rolls and beneath said core-roll, means to create a strong 70 frictional engagement between said belt and said compression-rolls, means to rotate said compression-rolls such that they may be operated simultaneously or independently of each other and stops to limit the approach of 75 the movable roll to the stationary roll, substantially as described.

9. In a cotton-press, the combination of a stationary compression-roll, a movable compression-roll, a core-roll movably supported 80 between said compression-rolls, a belt which passes over said compression-rolls and beneath said core-roll, a heavy roll supported in the bight of the belt beneath the press and means to rotate said compression-rolls such 85 that they may be operated simultaneously or independently of each other, substantially as described.

10. In a cotton-press, the combination of a stationary compression-roll, a movable compression-roll, a core-roll movably supported 90 between said compression-rolls, a belt which passes over said compression-rolls and beneath said core-roll, a roll supported above the stationary compression-roll, which holds 95 said belt in contact with said stationary roll and means to rotate said compression-rolls such that they may be rotated simultaneously or independently of each other, substantially as described.

11. In a cotton-press, the combination of a stationary compression-roll, a movable compression-roll, a core-roll movably supported between said compression-rolls, a belt which passes over said compression-rolls and beneath said core-roll, a roll supported above the stationary compression-roll so as to be adjustable toward and from the same, a tension-roll supported adjacent to the movable compression-roll and means to rotate the compression-rolls such that they may be operated simultaneously or independently of each other, substantially as described.

12. In a cotton-press, the combination of a stationary compression-roll, a movable compression-roll, a core-roll movably supported 115 between said compression-rolls, a belt which passes over said compression-rolls and beneath said core-roll, a heavy roll supported in the bight of the belt beneath the press, a 120 roll adjustably supported above the stationary compression-roll, a tension-roll supported adjacent to the movable compression-roll and means to rotate said compression-rolls so that they may be operated simultaneously or independently of each other, substantially as described.

In testimony that I claim the foregoing as my invention I hereunto set my hand this 11th day of September, 1896.

MAGNUS SWENSON.
